CLAIM

The ornamental design for an automatic soap dispenser, as shown and described.

DESCRIPTION

FIG. 1 is a front, left, top perspective view of the automatic soap dispenser, showing my new design; FIG. 2 is a rear, right, bottom perspective view thereof; FIG. 3 is a front elevational view thereof; FIG. 4 is a rear elevational view thereof; FIG. 5 is a left side view of the enlarged scale thereof; FIG. 6 is a right side view of the enlarged scale thereof; FIG. 7 is a top plan view of the enlarged scale thereof; and, FIG. 8 is a bottom plan view of the enlarged scale thereof. The dashed broken lines illustrate portions of the automatic soap dispenser which form no part of the claimed design.
